SAMUEL F. ARBUCKLE, OF INDIANAPOLIS, INDIANA.

INTERNAL-COMBUSTION-ENGINE VACUUM ACTUATING MEANS.

1,296,735.

Specification of Letters Patent. Patented Mar. 11, 1919.

Application filed January 28, 1918. Serial No. 214,169

To all whom it may concern:

Be it known that I, SAMUEL F. ARBUCKLE, a citizen of the United States, and a resident of Indianapolis, county of Marion, and State of Indiana, have invented a certain new and useful Internal-Combustion-Engine Vacuum Actuating Means; and I do hereby declare that the following is a full, clear, and exact description thereof, reference being had to 10 the accompanying drawings, in which like letters refer to like parts.

The object of this invention is the improvement of the construction and operation of vacuum actuating means associated with 15 internal combustion engines. Such vacuum actuating means may be used for operating brakes of automobiles or moving any other part where suitable.

One feature of the invention consists in an 20 improved construction of cylinder in communication with a vacuum line and the parts associated with the cylinder for utilizing the power resulting from the vacuum for actuating the desired means. The piston in 25 said cylinder has considerable peripheral area and the periphery thereof is of yielding material so there is relatively very slight wearing action between the piston and the cylinder resulting from the jarring of the 30 automobile or like structure with which the device is associated. This greatly prolongs the life of the cylinder and piston.

Another feature of the invention consists 35 in providing a spiral spring in the cylinder between the piston and vacuum end of the cylinder for actuating the piston, piston rod and actuated means when the degree of vacuum is diminished.

Another feature of the invention consists 40 in providing a hollow or chambered piston for containing permanent lubrication, the wall of the piston being made of leather so that the lubrication will slowly permeate the leather and lubricate the piston and cylinder. One filling of such piston will suffice 45 for a very long period of time. In addition to the foregoing idea is that of providing the piston rod, with a longitudinal lubricating passage communicating with the lubricating chamber in the piston, and mounting 50 a grease cup on the piston rod outside of the cylinder. This still further extends the

period during which one supply of lubrication will suffice to lubricate the device.

Another feature of the invention consists 55 in placing in the vacuum line a vacuum chamber for rendering more uniform the degree of vacuum in the line. If at one moment there is a relatively high degree of vacuum in the intake manifold of the engine, 60 it will create a relatively high degree of vacuum in the vacuum line and by having a check valve between the intake manifold and the vacuum chamber, this high degree of vacuum will be maintained in the line until 65 the device is operated, although the degree of vacuum in the intake manifold might become less. Also a safety valve is provided for said vacuum chamber.

A further feature of the invention is the 70 provision of an operating valve structure for the control of the cylinder in the vacuum line.

The full nature of the invention will be 75 understood from the accompanying drawings and the following description and claims:

In the drawings, Figure 1 is a side elevation of an internal combustion engine and some of the associated parts of an automobile, and said vacuum actuating means associated with the engine. Fig. 2 is a central vertical section through the cylinder and associated parts on a large scale, the parts being shown in idle or actuated position. Fig. 3 is the same with the parts in position when under the influence of the vacuum. Fig. 4 is a modified form of piston. Fig. 5 is an enlarged detail sectional view as seen on line 5-5 of Fig. 1. Fig. 6 is a detail sectional view of a modified form of cylinder and means to attach a pipe thereto. Fig. 7 is a sectional view of a modified form of operating valve.

In the drawings there is shown an internal combustion engine 10 of ordinary type used in automobiles and having a carburetor 11 and intake manifold 12. A pipe 13 leads from the intake manifold to a cylinder 14 which may be located anywhere with reference to the engine so that the piston rod 15 thereof can actuate the desired means to be actuated. In the drawings the actuated means consists of a bell crank lever 16 ful-

crumpled at 17 and operatively connected with a rod 18. This, however, is only typical of what will be referred to herein as the "actuated means". The pipe 13 and cylinder 14 5 may be called a vacuum line. There is in it a check valve 19.

The vacuum line is controlled by a valve 34 therein which is operated by an arm 35 and a rod 36 running therefrom to an arm 37 10 on a shaft 38 mounted in the dash board 20 of an automobile having a handle 39 turning the shaft and a dial 40 for indicating its position. The means for operating the valve 34, however, may be any suitable means depending upon what the engine is associated 15 with. By operating the valve 34, one is enabled to control the degree of vacuum in the cylinder 14. If the valve is entirely open, the degree of vacuum in the cylinder 14 20 would be exactly the same as in the portion of the pipe 13 between the two valves 19 and 34.

The cylinder 14 has a removable end to which the pipe 13 is secured and that may 25 be called the vacuum end of the cylinder. The piston on the piston rod 15 is forced or held against the other end of the cylinder, when the device is idle or the degree of vacuum low, by a spiral spring 41 lying be- 30 tween the piston and the vacuum end of the cylinder. This spring must be strong enough to actuate the piston when the degree of vacuum is relatively weak and the spring must be weak enough to yield when the de- 35 gree of vacuum is relatively strong.

The piston herein is formed of a cup-shaped metal member 22 which is slipped on the reduced end of the piston and opens 40 toward the suction end of the cylinder, and it is of less diameter than the cylinder. The open end of the metal member 22 of the piston is closed by a leather disk 23, the outer portion of which is turned over the periphery of the member 22 of the piston so as 45 to form a packing between the metal part 22 of the piston and the cylinder. A wide washer 24 is then placed on the piston rod and a narrow washer 25 thereon, and the whole tightened up and held by a nut 26, 50 the nut 26 and washer 25 being small enough to lie within the spring 41. The periphery of the piston is made relatively long by reason of the cup-shaped form of the member 22 so as to furnish a considerable bearing 55 surface whereby the wear between the piston and cylinder, due to the jarring of the automobile or the like, will be reduced to a minimum and greatly prolong the life of the device. The air end of the cylinder 60 has an opening 47 to the outer air.

With the foregoing construction of the piston there is a lubricating chamber 27 therein which is to be filled with grease and when made in the form shown in Fig. 4, this 65 chamber is closed by a screw plug 28, the

piston in said form being solid. This lubrication will permeate the leather very slowly and maintain the piston in a suitably lubricated condition for a very long period of time. To further prolong and improve the 70 lubrication of the piston, the piston rod is provided with a longitudinal passage 29 which communicates with the lubricating chamber 27 and with a grease cup 30 on the piston outside the cylinder. By filling 75 this grease cup with a lubricant or semi-liquid, it will serve as a fountain of supply for the lubricating chamber 27 in the piston.

To promote the uniformity of the degree of vacuum in the vacuum line, the reservoir or vacuum chamber 31 is connected with the pipe 13 between the two valves 19 and 34. The effect of this chamber is to increase the capacity of the vacuum line and maintain a maximum degree of vacuum. 85 Until the device is operated, the degree of vacuum in this vacuum chamber and in the vacuum line is that of the highest degree of vacuum which existed in the intake manifold previous thereto. The check valve 19 90 protects the degree of vacuum in this chamber and the line from any subsequent reduction in the degree of vacuum in the intake manifold.

The degree of vacuum in the intake manifold of an internal combustion engine creates quite a considerable power, more than would be expected by most people, so that this vacuum actuating apparatus is capable of performing quite a considerable work 95 and yet without materially affecting the operation of the engine, because the vacuum line 13 is extremely small, say a quarter of an inch or less. But to avoid any trouble in the vacuum line, a safety valve 32 is provided in the vacuum chamber 13 which permits the inlet of air from the outside when the degree of vacuum is so great as to overcome the action of the spring 33 which holds the valve closed. The tension of this spring 100 is adjusted by a nut 44 on the threaded end of the valve stem 45 and which screws down on the washer 46 that bears upon the outer end of the spring.

It is not necessary that the end of the cylinder 14 should be removable as shown in Figs. 2 and 3 and the modified form thereof as shown in Fig. 6, where the cylinder is drawn and made of one piece.

Instead of using the valve 34 and parts 120 employed for operating the same from the dash, that form of device shown in Fig. 7 may be used, which comprises a cylinder 50, having a piston 51 therein, said piston being moved longitudinally of the cylinder by 125 means of a pull rod 52. The cylinder 50 extends through the dash 20 and has both ends closed, the pipe 13^a corresponding to the pipe 13 being connected to the forward end of the cylinder and communicating 130

with the intake manifold. The tube 13^b connecting the actuated means with the cylinder, is attached to the cylinder at a point substantially midway between the ends of 5 the cylinder, so that the piston can be moved to position on either side of the opening in the tube 13^b.

The pull rod 52 is provided with a plurality of circumferential grooves 53 with 10 which coöperates a friction lock 54 designed to hold the piston in adjusted positions, whereby the piston may be positioned to open or close communication between the pipe sections 13^a and 13^b or partially open 15 communication therebetween to partially operate the actuated means. The piston 51 is constructed similar to the piston in the cylinder 14 and is self lubricating.

The invention claimed is:

20 1. Vacuum actuating means for internal combustion engines having an intake manifold, including a cylinder with one end in communication with the intake manifold of the engine and the other end open to the 25 external air, a cup shaped lubricant containing piston in said cylinder, a rod connecting the piston with the actuated means, and a valve for controlling the communication between the intake manifold and the cylinder. 30

2. Vacuum actuating means for internal combustion engines having an intake manifold, including a cylinder, a pipe leading from the intake manifold of the engine to 35 one end of said cylinder, a cup shaped lubricant containing piston in said cylinder, a fibrous substance for regulating the flow of the lubricant from the piston, a rod connecting said piston with the actuated means, a 40 valve for controlling said pipe, and a check valve between said controlling valve and the intake manifold.

3. Vacuum actuating means for internal combustion engines including a vacuum line, 45 a controlling valve therefor, a check valve for said line located between the engine and said controlling valve, a vacuum chamber associated with said line between said two valves, and a spring controlled safety valve 50 associated with said vacuum chamber.

4. Vacuum actuating means for internal combustion engines having an intake manifold, including a cylinder with one end in communication with the intake manifold of 55 the engine and the other end open to the external air, a relatively long cup shaped lubricant containing piston in said cylinder to prevent wear during vibration, a porous substance attached to the piston to regulate 60 the discharge of the liquid from the piston, a rod connecting the piston with the actuated means, and a valve for controlling the communication between the intake manifold and the cylinder.

65 5. Vacuum actuating means for internal

combustion engines having an intake manifold, including a cylinder with one end in communication with the intake manifold of the engine and the other end open to the external air, a hollow piston in said cylinder 70 adapted to hold lubrication, a porous cover for said piston for dispensing the lubricant, and a valve for controlling the communication between the intake manifold and the cylinder. 75

6. Vacuum actuating means for internal combustion engines having an intake manifold, including a cylinder with one end in communication with the intake manifold of the engine and the other end open to the 80 external air, a piston in said cylinder formed of a cup-shaped metal member, a leather disk closing the open end of said cup-shaped member and surrounding the periphery thereof to form packing between the piston 85 and cylinder whereby a lubricating chamber is formed in said piston, a rod connecting the piston with the actuated means, and a valve for controlling the communication between the intake manifold and the cylinder. 90

7. Vacuum actuating means for internal combustion engines having an intake manifold, including a cylinder with one end in communication with the intake manifold of 95 the engine and the other end open to the external air, a piston in said cylinder formed of a cup-shaped metal member, a leather disk closing the open end of said cup-shaped member and surrounding the periphery 100 thereof to form packing between the piston and cylinder whereby a lubricating chamber is formed in said piston, a piston rod on which said metal member and leather disk are mounted, a metal washer on the inner 105 end of said rod of substantially the same diameter as the metal member of the piston for holding the leather disk against said metal member, a nut on the inner end of the piston rod for holding the washer in 110 place, a rod connecting the piston with the actuated means, and a valve for controlling the communication between the intake manifold and the cylinder. 115

8. Vacuum actuating means for internal combustion engines having an intake manifold, including a cylinder with one end in communication with the intake manifold of the engine and the other end open to the 120 external air, a hollow piston in said cylinder adapted to hold lubrication, a porous substance connected with said piston for regulating the discharge of the liquid from the piston, a piston rod connected with said piston having a longitudinal chamber in it 125 communicating with the lubricating chamber in the piston, a grease cup secured to said piston rod outside the cylinder and communicating with the lubricating chamber in the piston rod, a rod connecting the piston 130

with the actuated means, and a valve for controlling the communication between the intake manifold and the cylinder.

9. Vacuum actuating means for internal combustion engines including a vacuum line, a cylinder with one end in communication with said vacuum line, a hollow lubricant

containing piston in said cylinder connected with the actuated means, and a fibrous substance carried by the piston for controlling the flow of the lubricant.

In witness whereof, I have hereunto affixed my signature.

SAMUEL F. ARBUCKLE.
